UNITED STATES PATENT OFFICE.

JOHN W. STONE, OF THORNTOWN, INDIANA.

GATE.

SPECIFICATION forming part of Letters Patent No. 430,221, dated June 17, 1890.

Application filed December 17, 1889. Serial No. 834,097. (No model.)

To all whom it may concern:

Be it known that I, JOHN W. STONE, a citizen of the United States, residing at Thorntown, in the county of Boone and State of Indiana, have invented a new and useful 5 Gate, of which the following is a specification.

This invention has relation to swinging gates of that class adapted to be opened and closed by foot passengers or by persons upon 10 horseback or in vehicles; and the objects and advantages of the invention, together with the novel features thereof, will be hereinafter described, and particularly pointed out in the claims.

15 Referring to the drawings, Figure 1 is a perspective of a gate constructed in accordance with my invention. Fig. 2 is a plan. Fig. 3 is a transverse section with the gate open, looking toward the latch-post. Figs. 4 and 5 are details in perspective of the latch 20 operating and guiding levers. Fig. 6 is a detail in elevation of one of the wire-twisters.

Like numerals of reference indicate like parts in all the figures of the drawings. 25 1 represents opposite sills, near the opposite ends of which are mounted the cross-sills 2.

3 represents the hinge-post, in the inner face of which are mounted the L-shaped 30 hinge-brackets. The post 3 is pivotally mounted between the sills 1 in front of the cross-sill 2, and in rear of the post there is mounted between the sills 1 a second post 5, connected to the post 3 by means of a metal 35 rod 6, having tappets on its threaded ends for securely binding the two posts together. By operating the tappets it will be apparent that the post 3 may be swung toward or from the post 5, thus raising or lowering the gate for 40 the purpose of adjusting the same or taking up any sag therein.

7 represents a diagonal brace, which extends from the lower end of the post 3 to near the upper end of the post 5.

45 8 represents the latch-post, which is mounted between the sills 1 in a similar manner as is the post 3, and in rear of the same is located the stationary post 9, braced against the post 8 by the inclined brace 10, and connected to 50 said post by the binding-rod 11. From each of the opposite sides of the posts 3 and 8 extend the inclined braces 12, the lower ends of

which are secured to the ends of the cross-sills 2, and preferably terminate in the ground.

13 represents a double catch secured to the 55 inner face of the post 8, said catch being provided with opposite inclined ends adapted to receive a latch moving in either direction, and above the catch there is mounted a locking-bar 14, slotted as at 15, and supported on 60 the post by means of a bolt 16. The bar 14 by gravity alone is suspended directly over the notch in the catch, and is of such a width as to cover the entrance to the same.

17 represents a limiting-bail, which em- 65 braces the bar 14 and limits its swing from over the notch in the catch.

The gate comprises a pair of rear hinged bars 18 and two pairs of vertical bars 20 at the opposite end of the same, said bars 20 be- 70 ing connected to the bar 18 by upper and lower longitudinal bars.

If desired, ordinary panel-rails may complete the gate; but in this instance I prefer to employ wire panels extending from the 75 bar 18 to the front pair of bars 20. The ends of the panel-wires pass through perforations formed in L-shaped wire-twisters 26, located at one end of the gate. The twisters comprise a shank 27, passed through suitable 80 openings in the hinge-bar of the gate and terminating in screw-threads, over which is introduced an adjusting and binding nut. The L end of the twister forms a handle 29 for rotating it to take up the slack wire, and 85 is provided at its extremity with a lug 30, which is drawn against the face of the bar by means of the binding-nut after a sufficient twist has been made. Between bars 20 are pivoted latches 31 and 32, the former being 90 at about the middle of the gate and the latter near the lower end, the ends of said latch-bars being extended slightly beyond the front pair of vertical bars 20. A spring 33 is connected at one end to the upper latch-bar 31, 95 and has its lower end connected to one of the vertical bars 20, and therefore normally maintains the front end of the upper latch-bar depressed.

34 represents a connecting link or bar piv- 100 otally connected at its opposite ends to the upper latch 31 and the lower latch 32, whereby said latches move in unison.

35 represents an arm connected at its lower

end to the upper latch-bar 31, and having its upper end projecting above the upper bar of the gate, which upper bar is projected beyond the hinge-post and consequently beyond the 5 pivotal point of the gate.

Upon the upper longitudinal bar of the gate, in front of the hinge-bar 18, there is pivoted at 36 an oscillating T-plate 37, the forward end of the said plate being bent at a 10 right angle to the bar and provided with two side perforations 38 and a central perforation 39. The rear end of the plate is also upturned and perforated, as at 40.

41 represents opposite pulley-posts carrying double pulleys 42, a post and a pair of pulleys being located at each side of the gate and in line with the hinge-post thereof. In the side perforations formed in the pivoted guide-plate are fastened operating-ropes 44, 20 one of said ropes taking over one of the pulleys at each side of the gate and terminating in a handle.

45 represents a rope attached to the upper end of the arm 35, the opposite end of the 25 rope being passed through the central perforation formed in the guide-plate, and also through the upturned and perforated rear end of said plate and connected to the upturned perforated end of a gate-closing lever

30 47, pivoted at 48 to the rear end of the upper gate-bar in rear of the hinge-post, said lever being formed with a central pair of transverse arms 50, the ends of which are downwardly turned at each side of the said

35 bar, and therefore limit the oscillations of said lever upon the bar. The rear end of the lever terminates in a transverse arm 52, perforated near its ends, and in the same are secured the inner ends of a pair of latch-operating ropes 53, each rope being passed over the unoccupied pulley at the adjacent side of the gate.

The operation of my invention is as follows: Taking the gate in a locked position, a 45 pull upon the terminals of either of the cords or ropes 44 oscillates the latch-operating plate and draws upon the cord or rope connecting the same with the latch, thus raising the latches. As the latch 31 is elevated, the gravity-bar 14 is raised and a further pull upon the rope 44 serves to open the gate in the same direction. When the gates are swung to one side, the lower latch 32 takes over the beveled end of a catch-post 55, one of which 50 is located at the base of each of the posts. To close the gate a pull upon the opposite rope 53 serves to release the latch 32 from the catch-post and swing the gate to, the catching of the upper latch 31 being insured by 55 the gravity locking-bar 14, which is forced to one side and by its bail is stopped and prevents the latch from passing out at the opposite side of the catch.

It is apparent that the gate-operating mechanism herein shown and described may be applied to gates of various constructions, and that the other elements of novelty need not

necessarily be included with the mechanism mentioned.

The inclined or diagonal braces are each 70 formed of two halves or sections 57 and 58, pivoted at their outer extremities to the corners of the gate-frame. The pairs of sections are of such a length when combined as to be greater than the exact distance from one 75 diagonal corner of the gate-frame to the other, and as their inner ends abut they are consequently at a slight angle to each other, the inner ends of the pair of sections 57 being beveled, as at 59, to rest within a V-shaped 80 notch 60 in the adjacent ends of the other pair of sections. Diagonally below this joint there is located a parallel pair of levers 61, the free ends of which abut against the lower 85 pair of sections 57, and consequently support said sections in position. The lower ends of the levers are connected by a cross-pin 21, which bears on the lower panel-rail of the gate. Now it will be apparent that swinging the lower end of the straining-lever toward 90 the hinge of the gate forces the sections more nearly into alignment with each other, and consequently raises the latch end of the gate-frame, and thus takes up any sag at that end.

Having thus described my invention, what 95 I claim is—

1. The combination, with the hinge-post and the opposite sills to which it is pivoted, of a rear rigid post and a binding-rod 100 adjustably connecting the upper ends of said posts, substantially as specified.

2. The combination, with the hinge-post and the opposite sills to which it is pivoted at its lower end, of a second post arranged in rear of the hinge-post, a diagonal brace connecting the lower end of the hinge-post with the upper end of the rear post, and an adjustable binding-rod connecting the upper 105 ends of the two posts, substantially as specified.

3. In a gate, the combination, with the opposite vertical end bars, one of which is provided with a series of transverse perforations, of a series of L-shaped twistlers loosely mounted in the perforations, each provided with a 115 transversely-perforated shank and a binding-nut at one end and at its opposite end beyond the bar bent to form an L-shaped operating end terminating in an inwardly-disposed locking-lug adapted to take against the 120 bar to prevent a rotation of the twister, and a series of wire panels having one of their ends connected with the perforations in the shanks and their opposite ends connected to the opposite vertical post, substantially as 125 specified.

4. The combination, with a gate the upper bar of which is extended in rear of its hinge and a latch pivoted to the front end of the gate and having an arm projected therefrom, 130 of a pivoted lever secured to the gate-bar in front of its hinge and a pivoted lever secured in rear of its hinge to the bar, a rope connecting the front end of the rear lever with

the latch-arm and passing through a guide-eye in the front lever and ropes connected to opposite sides of the two levers and terminating in hand-pulls, and posts at each side 5 of the gate provided with twin pulleys for the reception of the ropes, substantially as specified.

5. The combination, with the hinge-gate provided with an upper bar extending in rear 10 of the hinge and with opposite pivoted latches connected together, a spring for normally depressing the same, and a vertical latch-arm, of a latch-lever pivoted upon the gate-bar and having opposite upturned ends perforated, a 15 cord or rope passed through the same and connected at one end with the latch-arm, opposite cords for operating said latch-lever for opening the gate, a rear pivoted gate-operating lever having transverse arms bent to 20 brace the upper bar of the gate, and having its front end connected with the latch-operating cord and terminating at its rear end in a cross-bar, cords connected to the same, and opposite posts having twin pulleys for

the accommodation of the two cords at each 25 side of the gate, and catches for engaging the lower one of the latch-bars of the gate, substantially as specified.

6. The combination, with the gate-frame, of opposite diagonally-disposed bars pivoted 30 at their outer ends to the diagonally-opposite corners of the frame and having their adjacent ends abutting, said bars being of a combined length greater than the distance from one corner of the gate-frame to the diagonally-opposite corner, and a straining-lever 35 loosely interposed between one of said bars and a panel-rail of the gate and adapted to bind against said diagonal bars, substantially as specified. 40

In testimony that I claim the foregoing as my own I have hereto affixed my signature in presence of two witnesses.

JOHN W. STONE.
